Charles S. Pippin

UNITED STATES PATENT OFFICE.

CHARLES S. PIPPIN, OF COALDALE, WEST VIRGINIA.

ICE-CREAM-SHIPPING CAN.

Application filed March 30, 1923. Serial No. 628,808.

To all whom it may concern:

Be it known that I, CHARLES S. PIPPIN, a citizen of the United States, residing at Coaldale, in the county of Mercer and State 5 of West Virginia, have invented certain new and useful Improvements in an Ice-Cream-Shipping Can, of which the following is a specification.

This invention relates to cold storage 10 shipping can and more particularly to an improved receptacle or can in which ice cream may be frozen and shipped and maintained under a low temperature while the receptacle is in transit.

15 Another object of the invention is to provide a can or receptacle of this character which will include a coil of pipe adapted to be connected in the pipe line of a refrigerating system so that a number of the cans 20 or receptacles may be connected in series or individually to the refrigerating system while the freezing process is carried on.

A further object of the invention is to 25 provide a receptacle of this character which will be constructed so that the interior compartment will retain the cold for a considerable length of time so that the contents of the container will be maintained at a low temperature while the receptacle is being 30 shipped.

Other objects will appear upon consideration of the following detail description and accompanying drawing in which:

Figure 1 is a longitudinal section through 35 the device constructed in accordance with my invention.

Figure 2 is a top plan view thereof, and

Figure 3 is a cross section taken on the lines 3—3 of Figure 1.

40 Referring to the drawing by numerals the outer casing 1 is of cylindrical form and has a bottom wall 2 and an open top 3 to which is attached a tight cover 4 having spring latches 5 carried by the casing 1 and 45 adapted to be connected to suitable clip members on the cover whereby the latter will be held in tight engagement with the top of the casing when the cover is in applied position. Obviously the casing may 50 be of any size according to the quantity of material to be placed within the receptacle.

Arranged within the outer casing is the 55 inner receptacle 5 which also is of cylindrical form and of a diameter less than the interior diameter of the outer casing so that a space 6 is provided between the outer and

inner containers. Spacing members 7 are arranged in the space 6 to maintain the inner receptacle in proper spaced relation and a coil of pipe 8 is coiled around the outside of the inner receptacle 5, the coil extending from the upper to the lower end of the inner receptacle as shown. The ends of the coil of pipe 8 are extended through the wall of the outer casing to provide the connecting ends 9 and 10 which may be coupled to the system of piping used in the refrigerating system.

The top of the inner receptacle is provided with a tightly fitting removable cover 11 and the bottom wall of the inner receptacle is raised as indicated at 12 so that it will be above the bottom of the outer casing thus providing a bottom air space 13. The cover 11 is depressed as illustrated so 75 that an upper air space 14 is provided between the cover 11 and the cover of the outer casing so in this manner an air space is provided entirely around the inner receptacle through which a free circulation of 80 air may be had.

In use, the ice cream or other commodity will be placed within the inner receptacle and the cover 11 applied in position. The coil of pipe 8 is then connected in the refrigerating system and the temperature of the air in the air space will be gradually reduced until the contents of the inner receptacle is frozen and the pipes may then be disconnected from the refrigerating system 90 and receptacle utilized as a shipping container.

Minor changes may be made in the details of construction without departing from the spirit of the invention or the scope 95 of the claims hereunto appended.

Claims:

1. A shipping receptacle of the character described comprising an outer casing, a removable cover for the casing, latch spring carried by the outer casing and engageable with the cover to maintain the latter in air tight engagement with the outer casing, an inner receptacle placed within the outer casing and in spaced relations thereto, whereby 100 an air space is provided entirely around the inner receptacle, a cover for the inner receptacle spaced from the cover of the said outer casing whereby an upper air space is provided above the inner receptacle, the bottom wall of the inner receptacle being raised 105 to provide a bottom space between the bot-

tom of the outer casing and the inner receptacle, and a coil of pipe surrounding the inner receptacle and having its ends extended through the walls of the outer casing.

2. A device of the character described comprising an outer casing of cylindrical form having an open top provided with an air tight removable cover, an inner receptacle of a diameter less than the diameter of said outer casing whereby an annular space is provided between the inner receptacle and the outer casing, means interposed between the inner receptacle and the outer casing to maintain the inner receptacle in spaced relation from the wall of the outer casing, the bottom of the inner receptacle being elevated to provide a bottom air space in communication with the said annular air

space, a removable cover for the said inner receptacle, the said cover being depressed to provide a top space between the receptacle cover and the cover for the said outer casing, said top space being in communication with the said annular air space, 20 a coil of pipe extending around the inner receptacle from the top to the bottom thereof, the opposite terminals of the said coil of pipe being extended through the wall of the outer casing at diametrically opposite 25 points.

In testimony whereof, I have affixed my signature in the presence of two witnesses.

CHARLES S. PIPPIN.
